[57] **CLAIM**

The ornamental design for a hand held pull-out spray, as shown and described.

DESCRIPTION

FIG. 1 is a top, front perspective view of a hand held pull-out spray showing my new design;

FIG. 2 is a top, rear perspective view thereof;

FIG. 3 is a top plan view thereof;

FIG. 4 is a right side elevational view, the left side being a mirror image thereof;

FIG. 5 is a rear elevational view thereof;

FIG. 6 is a front elevational view thereof;

FIG. 7 is a bottom plan view thereof;

FIG. 8 is a top, front perspective view of a second embodiment of the hand held pull-out spray, differing from the embodiment of FIG. 1 in that it has a longer handle;

FIG. 9 is a right side elevational view of the pull-out spray illustrated in FIG. 8, the left side being a mirror image;

FIG. 10 is a top, front perspective view of a third embodiment of the hand held pull-out spray, differing from the embodiment of FIG. 1 in that it has a shorter handle; and, FIG. 11 is a right side elevational view of the pull-out spray illustrated in FIG. 10, the left side being a mirror image.
